UNITED STATES PATENT OFFICE.

JOHN J. BOHLER, OF WESTFIELD, MASSACHUSETTS.

WHIP-LASH ATTACHMENT.

SPECIFICATION forming part of Letters Patent No. 375,984, dated January 3, 1888.

Application filed October 8, 1887. Serial No. 251,845. (No model.)

To all whom it may concern:

Be it known that I, JOHN J. BOHLER, a citizen of the United States, residing at Westfield, in the county of Hampden and State of Massachusetts, have invented certain new and useful Improvements in Whip-Lash Attachments; and I do declare the following to be a full, clear, and exact description of the invention, such as will enable others skilled in the art to which it appertains to make and use the same.

My invention has relation to whips; and it consists in the novel construction of a snap, as hereinafter specified and claimed.

The invention will be fully understood from the following description and claims when taken in connection with the annexed drawings, in which—

Figure 1 is a view of a whip, showing my invention applied thereto. Fig. 2 is a view of my improved snap ready to be applied to a broken whip.

Referring to the said drawings by letter, A designates a whip with my improved lash attached thereto.

B indicates the place of junction.

C indicates the whip-snap ready to be applied to a whip needing repair.

Carriage-whips are now usually constructed with a stock or handle of wood, metal, or leather of considerable rigidity and terminating in a snap of closely-woven fibrous material, so that when in their sockets or the driver's hands the whip appears curved, as represented in Fig. 1 of the drawings. The usual method of construction consists in covering the whip-stock with the same material that constitutes the snap by weaving the same closely around it, and then after passing the body of the stock weaving the snap thereon. This mode of construction is subject to the defect that in case the whip breaks or becomes too badly worn for use the whip is useless and is necessarily thrown away. To remedy this defect is the

object of my invention. I construct a snap of the description shown on Fig. 2 of the drawings and marked C. This snap is preferably formed of closely-knitted fibrous material, and is provided at its outer end with a snap, C, composed of loose threads. The opposite end of this snap is constructed with a loop, as shown at g, and also a removable loop, y, the free end of which is composed of loose threads, as represented, to provide for ready attachment to the whip. It will be observed that when in use these loops g and y are united by passing one loop through the eye of the other.

My method of attaching the snap to a broken or useless whip is as follows: I first sever the useless portion from the whip proper and cut away or trim the upper end of the whip sufficiently to render it somewhat pointed. I next wax said pointed end, and also the loose threads of the loop y, and then, after arranging said loose threads carefully around the pointed end of the whip, wrap said threads closely and securely around the whip-point by waxed thread, wire, or any other suitable means.

It will be observed that my invention is not especially designed for use in the manufacture of whips; but it is intended mainly for the repair of whips that have been broken or rendered useless by wear.

Having described my invention, what I claim is—

As an improved article of manufacture, the whip-snap C, provided with a loose threaded outer end and with the loops g and y, the free ends of the latter having loose threads for attachment to a whip, substantially as specified.

In testimony whereof I affix my signature in presence of two witnesses.

JOHN J. BOHLER.
